UNITED STATES PATENT OFFICE.

JOHANNES BECKMANN, OF ALTONA-OTTENSEN, GERMANY.

EXPLOSIONPROOF FITTING FOR ELECTRIC GLOWLAMPS.

Application filed November 30, 1926, Serial No. 151,792, and in Germany March 3, 1926.

This invention relates to an explosion proof fitting for electric glow-lamps, and more particularly to an improved safety switch for the same which prevents the 5 glow-lamp being switched-on with open fitting and thus avoids any formation of dangerous sparks, while it allows a switching-on of the glow-lamp in the closed position of the fitting only.

10 The accompanying drawing illustrates the improvement: Figs. 1 and 2 are longitudinal sections through the explosionproof fitting with the glow-lamp, in its closed and open position respectively; Figs. 3 and 4 show a 15 detail thereof on a larger scale, in the closed and open position of the fitting respectively; Fig. 5 is a section on the line 1—1 of Fig. 1 on a larger scale.

A non-turnable slide 1 is arranged in a 20 casing 2 of the stationary member 3 of the fitting and acted upon by a pressure-spring 4. Said slide is slotted at 5 and there adapted, in the open position of the fitting, to straddle, by action of the spring 4, a flattened member 6 of a switch axle thereby 25 locking the latter against turning and thus preventing a switching-on of the glow-lamp 7 in the open position of the hinged member 8 of the fitting. The latter is pivoted at its 30 rear end 13 and has at its front end a lug 11 with an open-ended key-hole 9, 10 therein, which when closing the fitting and in the closed position thereof retracts the slide 1 against the action of the spring 4 and enters 35 the open end of the casing 2 so far that the flattened part 6 of the switch axle is located within the round boring 10 of the keyhole 9, 10 and can then be freely turned therein, thereby allowing a switching-on of

the glow-lamp in the closed position of the 40 fitting only. Besides, the switched-on position of the flattened part 6 of the switch axle (Fig. 1) prevents an opening of the fitting even after loosening of the fastening-screws 45 12 thereof as long as the glow-lamp is alight. The latter must first be switched-off by turning the switch axle so that its flattened part 6 assumes the position ready for entering the slot 9 of the keyhole 9, 10, in which it is, after opening of the hinged part 8, again 50 locked by the rebounding slide 1 (Fig. 2).

What I claim, is:—

The combination, in an explosion proof fitting for electric glow-lamps, of a flattened switch axle part, a stationary fitting member 55 and a hinged fitting member, fastening-screws to close said hinged fitting member upon said stationary fitting member, an open-ended casing integral with said stationary fitting member, a spring-influenced non- 60 turnable slide in said casing having a slotted end and adapted to straddle therewith the flattened switch axle part and thus to prevent a turning thereof in the open position of the hinged fitting member, a lug on the 65 hinged fitting member having an open-ended keyhole therein and adapted to enter the open end of the casing and to retract said slide while receiving the flattened switch axle part in the round boring of its keyhole 70 and allowing a turning thereof in its closed position only, said flattened switch axle part in its switched-on position preventing an opening of the hinged fitting member even after loosening of said fastening-screws. 75

In testimony whereof I have hereunto set my hand.

JOHANNES BECKMANN.
